UNITED STATES PATENT OFFICE

155,789

DESIGN FOR AN AUTOMOBILE BODY

Harley J. Earl, Grosse Pointe Farms, Mich., assignor to General Motors Corporation, Detroit, Mich., a corporation of Delaware

Application February 18, 1948, Serial No. 144,560

Term of patent 7 years

(Cl. D14—3)

To all whom it may concern:

Be it known that I, Harley J. Earl, a citizen of the United States, residing at 217 Tourain, Grosse Pointe Farms, in the county of Wayne and State of Michigan, have invented a new, original, and ornamental Design for Automobile Bodies, of which the following is a specification, reference being had to the accompanying drawings, forming part thereof.

Figure 1 is a front and side perspective view of an automobile body, showing my new design.

Figure 2 is a rear and side perspective view thereof.

Figure 3 is a side elevation of the body.

Figure 4 is a half front elevation of the body.

Figure 5 is a half rear elevation of the body.

The dotted line showing in the several drawing figures is for illustrative purposes only.

I claim:

The ornamental design for an automobile body, as shown and described.

HARLEY J. EARL.
